GARMENT PRESSING MACHINE

Herbert E. Page, Syracuse, N. Y.

Application June 29, 1933, Serial No. 678,227

8 Claims. (Cl. 38—41)

This invention pertains to a garment or ironing press, and more particularly to that type wherein motor means is employed to effect the pressure upon the articles being pressed.

One of the objects is to provide simple and efficient means, actuated by a fluid pressure motor, to move one of the pressing elements from its extreme open position to a point where it is almost in contact with the other pressing element, using little power for this operation so as to conserve same for use when the pressing elements are brought in contact.

Another object is to provide means, actuated by the same fluid pressure motor, for suddenly greatly increasing the pressure between the pressing elements as they are brought in contact with one another.

Another object is a simple and economical lever mechanism of the general type of my application Ser. No. 653,380, filed Jan. 27, 1933, which initially applies the power of an actuator to quickly preliminarily close the press with a small movement of the actuator through a comparatively small leverage and to finally close the press through a great, powerful leverage with a greater movement of the actuator, or a mechanism for transferring the movement of an actuator to the movable pressing element, or head, carrying lever, through a differential lever mechanism automatically operable to quickly close the press through one leverage and to shift to a more powerful leverage automatically to finally close the press when the press head encounters resistance.

A further object is to provide means to maintain the press in a closed position, after it has once been closed by the operator, without further attention from the operator, and means to allow the press to open automatically from this position if the fluid pressure supply is temporarily interrupted and means to prevent the press from closing again when the fluid pressure supply is again continued unless it is closed in the regular manner by the operator.

Another object of the invention is an actuating mechanism for the movable element or head of the pressing machine, consisting of a head carrying lever and a second lever which are successively movable to close the press under heavy pressure, a motor, including a cylinder carried by or thrusting against one lever and a piston having its rod thrusting against the other lever whereby the levers move in opposite directions together with means preferably coacting means on the levers themselves for delaying the movement of the second lever until the press is closed

and then permitting movement of the second lever to transfer its movement to the head carrying lever to close the press under final pressure; or in other words, an actuating mechanism, including scissor-like levers with a motor carried by the levers for actuating the levers successively.

It further has for its object a floating motor between two successively actuated levers operating to close the press, whereby the force of the motor first acts with a short leverage to close the press through the head carrying lever and with a long leverage through the second lever and the head carrying lever to close the press under final pressure or levers or other means utilizing both the action and reaction of the motor parts to preliminarily and finally close the press.

In the drawings:—

Figure 1 is a side elevation, partly in section, in which the movable pressing element and its actuated means is shown by full lines in an extreme open position and by dotted lines in a nearly closed position.

Figure 2 is a similar view, the press being closed and the parts in position to produce great pressure.

This pressing machine mechanism comprises, generally, cooperating pressing elements, that is, a buck and a head movable toward and from the buck, a head carrying lever pivoted between its ends to the frame of the machine and carrying the head on its front arm, means for actuating the lever including a motion transmitting part and connections between said part and the rear arm of the lever to successively apply power to said arm between its ends and at its rear end.

The motion transmitting part is here shown as a fluid pressure cylinder connected by trunnion means to the rear arm of the head carrying lever said cylinder having a piston rod connected to the front arm of a second lever, said lever being pivoted between its ends to the frame of the machine and having a roller pivotally mounted in its rear arm.

The rear arm of the second lever normally contacts with means to hold it from pivotal movement, and moves out of engagement with said means when the press approaches preliminary closed position and into engagement with a fulcrum on the rear arm of the head carrying lever to permit pivotal movement of the second lever and actuate the head carrying lever through a high, powerful leverage.

In said drawings, 1 is the base of the machine and is adapted to rest upon a table or bench and

upon said base is mounted the buck support 2 and the buck 3.

Pivotaly mounted at 4 on the upper end of a vertically extended projection 5 of the main base 5 is a head carrying lever having two arms 6 and 7 and having connected to the arm 6 the press head 8.

Said head and the buck 3 may be of any shape and equipped with the regular covering or finish required by the work undertaken.

Pivotaly mounted on the arm 7 by means of the trunnion ring 9 and the trunnion 10 is a cylinder 11 in which is reciprocally mounted a piston having a downwardly extending piston rod 12 pivotally connected at its lower end by means of the pin 13 to the lever 14, Figure 2.

The lever 14 has a roller 15 pivotally mounted at 16 at the rear of said lever and the roller 15 is adapted to engage, under conditions presently described, with the surface 17 at the rear of the arm 7, Figure 1.

The roller 15 is also adapted to engage with the fulcrum surface 18 located on the lower side of the arm 7, Figure 2.

25 The arm 14 is pivotally mounted at 19 on the sliding or vertically adjustable member 20 said member having a threaded rod 21 located in its lower end, Figure 2.

The rod 21 passes through the horizontal projection 22 of the base 1 and has a bevel gear 23 secured at its lower end, said gear 23 meshes with the bevel gear 24, Figure 2.

30 The bevel gear 24 is mounted on a rod 25 which passes through the projection 26 of the base 1 and through the forward end of the base 1 and terminates in the hand adjustment wheel 27, Figure 2.

35 It will now be observed that turning the hand adjustment wheel 27 transmits this motion 40 through the rod 25 and the bevel gears 24 and 23 to the threaded rod 21 and thus causes the member 20 to raise or lower between the guides 28 and 29, Figure 2.

45 A retracting spring 30 is connected at its lower end at 31 to the arm 14 and at its upper end at 32 to the arm 7 and acts to yieldingly hold the arm 14 in the position as shown in Figure 1 with the stop or projection 33 of the arm 14 held against the stop 34 of the base 1, and the arm 7 50 held against the stop pin 35 located in the projection 5 of the base 1.

55 Pivotaly mounted on the base 1 at 36 is a bell crank lever consisting of three arms, 37, 38 and 39. The arm 37 has a retracting spring 40 attached at the end of said arm and the other end of the retracting spring 40 is secured at 41 to the base 1 and acts to yieldingly hold the arm 37 against the stop pin 42 with the bell crank lever arms 38 and 39 in the position as shown in Figure 1.

60 The arm 38 has pivotally mounted at its lower end a pawl 43 said pawl being adapted to engage with the pin 44 located near one end of a piston rod 45. The other, or forward, end of the piston rod 45 is attached to a piston having three large diameters, 46, 47 and 48 and two smaller diameters, 49 and 50 and said piston is reciprocally mounted in the piston valve cylinder 51, Figures 1 and 2.

70 The pawl 43 has a horizontally projecting arm 52 which is adapted to engage with the roller 53 mounted on the end of the arm 54 of a bell crank lever, said lever being pivotally mounted at 55 on the base 1 and having an upwardly extending arm 56 to the upper end of which is

attached the rod 57 said rod passing through the buck support 2 and having a knob 58 at its forward end, Figures 1 and 2.

The pawl 43 has a retracting spring 59 attached to the arm 53 of said pawl and this spring acts 5 to yieldingly hold the arm 52 in contact with the roller 53 at all times as shown by Figure 1 and by the full and dotted lines in Figure 2.

The roller 53 tends to keep the arm 52 in approximately a horizontal position due to the arm 10 56 resting against the stop pin 60 thus maintaining the engagement of the pawl 43 with the pin 44, however if the knob 58 is pushed rearwardly by the operator this motion is transmitted by the rod 57 and the bell crank arms 56 and 54 15 to the roller 53 and causes said roller to move downwardly thus depressing the arm 52 and raising the pawl 43 disengaging said pawl from the pin 44 as shown by the full and dotted lines in Figure 2.

20 The piston valve rod 45 has a retracting spring 61 attached to the rear end of said rod and this spring acts to yieldingly hold the rod 45 and its attached piston as shown in Figure 1 with the piston 46 against the stop 62; therefore when the piston valve is in the position as shown in Figure 2, if the knob 58 is pushed rearwardly when the pawl 43 disengages from the pin 44 then the piston of the piston valve will assume the position as shown in Figure 1 due to the action of the 30 spring 61.

The arm 39 is normally held in the position as shown in Figure 1 by the action of the spring 40 and said arm is adapted to engage with the piston rod head 63 when said head moves from the position as shown in Figure 1 to that shown in Figure 2 and this engagement causes the arm 39 to swing downwardly about the pin 36; this motion of the arm 39 is transmitted through the arm 38 to the pawl 43 and causes said pawl to 40 move from the position as shown by Figure 1 to the position shown by the full lines in Figure 2; this motion of the pawl 43 is transmitted through the pin 44 to the piston valve rod 45 and causes said rod and its attached pistons to move within 45 the piston valve cylinder 51 from the position as shown in Figure 1 to the position shown in Figure 2.

The upper cylinder head of the cylinder 11 is connected by means of the conduit 64 and the T 50 connection 65 and the conduit 66 to the fluid pressure supply valve 67; said valve is connected by the conduit 68 to a source of fluid pressure supply and may be any ordinary type of self closing valve such as is commonly used for this purpose and is mounted on the buck support 2 and adapted to be opened by an operating handle 69.

The side outlet branch of the T connection 65 is connected by means of the conduit 70 to a 60 port 71 located approximately in the center of the piston valve cylinder wall 51.

There are two other ports in the cylinder wall 51; the port 72 is located to the rear of the port 71 and is connected by the conduit 73 to the 65 same source of fluid pressure supply that supplies the valve 67, Figures 1 and 2.

The third port 74 enters the cylinder wall 51 in front of the port 71 and is connected by the conduit 75 to the fluid pressure shut-off valve 70 76 said valve being mounted on the base 1 and being adapted to be operated by the operating handle 77; the valve 76 may be of any self opening type, that is a type of valve that is held open by spring or other means and may be closed only 75

by depressing the handle 77, and this valve is connected by means of the conduit 78 to the atmosphere, Figures 1 and 2.

It will now be understood that the fluid pressure supply valve 67 will normally remain closed at all times unless the operator depresses the operating handle 69, while the fluid pressure shut-off valve 76 will normally remain open at all times unless the operator depresses the operating handle 77 thus shutting off the valve.

In order to cause the press to close, fluid under pressure must enter the cylinder 11, therefore it is necessary for the operator to depress both of the handles 69 and 77 because, with the press in the open position as shown by the full lines in Figure 1, if the handle 69 alone is depressed then fluid under pressure contained in the conduit 68 will flow through the valve 67 into the conduit 66, but instead of continuing through the T connection 65 and the conduit 64 and performing work in the cylinder 11, it will be free to flow through the side outlet of the T connection 65, through the conduit 70 and the port 71 and into the space 79 which exists between the smaller piston diameter 50 and the cylinder wall 51, from said space the fluid is free to flow through the port 74 and the conduit 75 and the valve 76, which normally remains open, and then through the conduit 78 and escape to the atmosphere.

Therefore, in order to prevent the escape of the fluid, the operator must also depress the handle 77, thus closing the valve 76; when this is done, the fluid, having no further escape through the valve 76 must continue on through the T connection 65 and the conduit 64 to the cylinder 11 and cause the press to operate, in this manner both hands of the operator are kept occupied during the closing operation of the press and the danger of the operator having a hand caught between the pressing elements is eliminated, Figure 1.

When fluid under pressure enters the cylinder 11, it tends to force the piston and its attached piston rod 12 downwardly and also acts upwardly against the top cylinder head of the cylinder 11 and tends to force said head and the attached cylinder 11 upwardly, Figure 1.

The downward force of the piston rod 12 acting through the pin 13 tends to rock the lever 14 in a clockwise direction about the pin 19, but is prevented from doing so because the roller 15 rests against the surface 17 on the arm 7, said surface may be of any shape suitable for the purpose but is shown in this instance as a radius drawn from the center of the pin 4, and thus prevents a clockwise rotation of the lever 14, Figure 1.

However, the upward force of the fluid pressure acting through the cylinder 11 is transmitted through the trunnion ring 9 and the trunnion 10 to the arm 7 and causes said arm to rock in a clockwise direction about the pin 4; this motion is transmitted through the arm 6 to the press head 8 and continues until the press has moved from the position as shown by the full lines to that shown by the dotted lines in Figure 1.

It will be observed that the force which moves the head from the position as shown by the full lines in Figure 1 to that shown by the dotted lines, which is a major portion of the total head travel, will be relatively small, since the power of the cylinder 11 acting through the trunnion 10 has a moment arm equal only to the distance from the center of the trunnion 10 and the center

of the pin 4 as compared with the distance from the center of the pin 4 and the center of the press head 8, therefore the power of the cylinder 11 is conserved for use later on when the press head 8 is actually in pressing position.

As the press head 8 approaches the pressing position, the surface 17 moves from the position as shown by the full lines to that shown by the dotted lines in Figure 1 at which point the roller 15 reaches the end of said surface thus releasing the lever 14 and allowing the piston rod 12 to rock the lever 14 in a clockwise direction about the pin 19 thus forcing the roller 15 onto the surface 18 and the parts will move from the position as shown by the dotted lines in Figure 1 to that shown in Figure 2.

It will now be observed that the force acting upwardly on the arm 7 has been greatly increased due to the downward force of the piston 12 having been suddenly brought into effect and multiplied by means of the lever 14 using the pin 19 as a fulcrum point and exerting a great upward pressure through the roller 15 and the surface 18 to the arm 7 and this force is transmitted through the arm 6 to the press head 8 during the movement of the parts from the position as shown by the dotted lines in Figure 1 to that shown in Figure 2.

A variation of pressure between the pressing elements can be secured by raising or lowering the fulcrum pin 19 by turning the hand adjustment wheel 27, as previously described, located at the front of the press, Figure 2; also, by this means, various thicknesses of articles can be accommodated between the pressing surfaces.

As soon as the fluid pressure in the cylinder 11 is released, the retracting spring 30 will rock the arm 14 from the position as shown in Figure 2 to that shown in Figure 1 with the stop 33 against the stop 34 at which point the surface 17 will be free to roll past the roller 15 from the position as shown by the dotted lines in Figure 1 to that shown by the full lines with the arm 7 resting against the stop pin 35.

When the operator has caused the press to close by depressing both of the operating handles 69 and 77 and the press has reached the position as shown in Figure 2, it will not be necessary for him to continue to hold down said handles in order to maintain the press in a closed position because as the piston rod 12 approaches the bottom of its stroke the piston rod head 63 engages with the arm 39 and, as previously explained, causes the pawl 43 to move the piston valve rod 45 and its attached piston from the position as shown in Figure 1 to that shown in Figure 2, similar to the movement of a piston valve in a steam engine, and it will now be observed that in the position as shown in Figure 2 that one of the larger piston diameters, as 47, 60 has now moved to a point where it closes the port 74 which leads, through the conduit 75, to the valve 76, therefore it is no longer necessary for the operator to keep this valve closed manually.

Furthermore, the space 80 which exists between the smaller piston diameter 49 and the cylinder wall 51, has been moved to a point where it connects the port 71 directly with the fluid pressure supply port 72, therefore, since this fluid pressure supply can now pass through the port 71 and the conduit 70, through the T connection 65 and the conduit 64 into the operating cylinder 11, it is no longer necessary for the operator to keep the fluid pressure supply valve 67 open any

longer and the operating handle 63 can be also released, Figure 2.

Therefore, when the press reaches a closed position as shown in Figure 2, it will remain in this position without further attention from the operator, as both operating handles can be released, and the press will remain closed as long as fluid pressure supply is maintained or until such time as the operator desires to cause the press to open; in this position the operating cylinder 11 acts in a manner similar to a single acting steam engine or steam pump with the piston at the end of its stroke only in this instance, instead of the motion of the piston being used to cause the piston valve to admit fluid pressure to the other side of the piston in the cylinder 11, and thus cause a reciprocating action as in an ordinary steam engine, it is desired to maintain the piston in the cylinder 11 at the end of its stroke and continual automatic reciprocation is not desired because in this case the normal power movement of the piston rod 12 is accomplished manually as it was done in the earliest days of the steam engine.

When the operator desires to open the press from the position as shown in Figure 2, this can be accomplished by pushing the knob 58 from the position as shown by the full lines in Figure 2 to that shown by the dotted lines; this motion is transmitted, as previously described, through the rod 57 to the bell crank arms 56 and 54 and causes the roller 53 to depress the arm 52, thus raising the pawl 43, as shown by the dotted lines in Figure 2 and releasing the pin 44 which allows the retracting spring 61 to draw the piston valve rod 45 and its attached piston rearwardly until the larger piston diameter 46 rests against the stop 62 and the piston valve has assumed the position as shown in Figure 1.

This motion of the piston valve moves the space 80, containing the fluid under pressure, away from the port 71, thus cutting off the fluid pressure supply and brings the space 79 into a position where it connects the port 71 directly with the port 74, thus allowing any remaining fluid under pressure that remains in the operating cylinder 11 to escape through the port 74 and the normally open valve 76 to the atmosphere and thereby allowing the retracting spring 30 to open the press, Figure 1.

When the press moves to the open position as shown by the full lines in Figure 1, the piston rod head 63 moves upwardly and disengages from the bell crank arm 39 and the retracting spring 40, acting through the arm 37, rocks the arm 38 in a clockwise direction about the pin 36, thus moving the pawl 43 rearwardly from the position as shown in Figure 2 to that shown in Figure 1 at which point said pawl can again engage with the pin 44 in which position it will be ready for the next closing operation of the press.

It will also be noted that if, when the press is in the fully closed position, as shown in Figure 2, the fluid pressure supply should for any reason fail temporarily and allow the press to open, then the piston rod head 63 would disengage from the arm 39 and allow the pawl 43 to swing rearwardly to the position as shown in Figure 1, and the retracting spring 61 would draw the piston valve rod 45 and its attached piston to the position as also shown in Figure 1 and the space 80 would thus be moved to the rear and the port 71 would be disconnected from the port 74, therefore if the fluid pressure supply were again resumed, the press would not close itself, since the port 71

would have been disconnected from said fluid pressure supply by the opening of the press, and said press could only be caused to close again by the operator depressing the operating handles 69 and 77 in the regular manner, in this manner if the operator found the press open and was not aware of the temporary discontinuance of the fluid pressure he could not become injured by the sudden closing of the press due to the fluid pressure being suddenly resumed.

10

I claim:

1. In a pressing machine, a suitable frame, a buck carried by the frame, a head movable toward and from the buck, a head carrying lever pivoted to the frame, a second lever pivoted to the frame, a motor including a cylinder and piston, the cylinder being carried by one of the levers and the piston having its rod connected to the other of said levers, the levers having coacting means for normally holding the second lever from movement during the preliminary closing of the press and permitting movement of the second lever when the head carrying lever has carried the head into coaction with the buck, and the levers having coacting means whereby the second lever transfers movement to the first during the movement of the second lever, and means for controlling the flow of motive fluid to and from the cylinder.

25

2. In a pressing machine, a suitable frame, a buck mounted on the frame, a head movable toward and from the buck, actuating mechanism for the head including successively operated levers movable in opposite directions, one of said levers carrying the head, a motor including a cylinder and a piston therein, the cylinder thrusting against one of said levers and the piston having its rod thrusting against the other of the said levers, said levers having coacting means for normally preventing pivotal movement of the second lever until the head carrying lever has moved the head into coaction with the buck and the levers having coacting means for transferring the pivotal movement of the second lever to the first head carrying lever, when the latter has carried the head into coaction with the buck, and means for controlling the flow of motive fluid to and from the cylinder.

35

3. A pressing machine including a suitable frame, a buck, a head movable toward and from the buck, and actuating mechanism for the head including a head carrying lever pivoted to the frame, a second lever pivoted to the frame, a motor carried by the levers and including a cylinder and a piston movable in the cylinder connected respectively to said levers, the part of the motor connected to the head carrying lever being located relatively near the pivot of the head carrying lever, the levers having coacting means for normally holding the second lever from movement, and said levers also having coacting means located at a point more remote from the pivot of the head carrying lever than the point where the motor is connected to the head carrying lever, for transferring the movement of the second lever to the head carrying lever, and means for controlling the flow of motive fluid to and from the cylinder.

50

4. In a pressing machine, a suitable frame, a buck carried by the frame, a head movable toward and from the buck, and actuating mechanism for the head, including a head carrying lever pivoted to the frame, a second lever pivoted to the frame, a motor carried by the levers and having two relatively movable parts connected to said levers respectively, and means for utilizing both action

60

65

70

75

75

and reaction of said motor for producing final pressure between the head and the buck.

5. In a pressing machine, a frame, a buck carried by the frame, a head movable toward and from the buck, a head carrying member pivoted to the frame, a second member pivoted to the frame, a motor including a cylinder and piston, the cylinder being carried by one of the members and the piston having its rod connected to the other of said members, the members having co-acting means for normally holding the second member from movement during the preliminary closing of the press and permitting movement of the second member when the head carrying member has carried the head into coaction with the buck, and the members having coacting means whereby the second member transfers movement to the first during the movement of the second member, and means for controlling the flow of motive fluid to and from the cylinder.

6. In a pressing machine, a frame, a buck mounted on the frame, a head movable toward and from the buck, actuating mechanism for the head including successively operated pivoted members movable in opposite directions, one of said members carrying the head, a motor including a cylinder and a piston therein, the cylinder thrusting against one of said members and the piston having its rod thrusting against the other of the said members, said members having co-acting means for normally preventing pivotal movement of the second member until the head carrying member has moved the head into coaction with the buck and the members having

coacting means for transferring the pivotal movement of the second member to the first head carrying member, when the latter has carried the head into coaction with the buck, and means for controlling the flow of motive fluid to and from the cylinder.

7. In a pressing machine, a frame, a buck carried by the frame, a head movable toward and from the buck, and actuating mechanism for the head including a head carrying member pivoted to the frame, a second member pivoted to the frame, a motor carried by the members and having two relatively movable parts connected to said members respectively, and means for utilizing both action and reaction of said motor for producing final pressure between the head and the buck.

8. In a pressing machine, a suitable frame, co-operating pressing elements having an opening and closing movement, and means for supporting said elements and effecting the opening and closing movement thereof including a motor having two relatively movable parts, one connected to one of said elements through a relatively short leverage means to effect the preliminary closing of the press, and the other to one of said elements through a second relatively long leverage means to effect the final closing of the press under heavy pressure, and means for holding the long leverage means from movement during the preliminary closing of the press, and thereby successively utilizing the action and reaction of the motor to preliminarily and finally close the press.

HERBERT E. PAGE.
